CONNECTING ELEMENT FOR
LARSEN-SHEET PILESCROSS REFERENCE TO RELATED
APPLICATIONS

This application claims priority to and is a United States National Phase Patent Application of International Patent Application Number PCT/EP2018/072311, filed on Aug. 17, 2018, which claims priority to German Patent Application No. 10 2017 007 798.3, filed on Aug. 21, 2017, both of which are incorporated by reference herein.

The invention relates to a profiled connection section with a constant cross-section for coupling at least two Larsen sheet piles at an angle of 90°, comprising two identically configured hooked strips, wherein each hooked strip has a hook-shaped hook section, a lock base, which adjoins one end of the hook section and runs in a straight manner, and a stop, which adjoins the lock base perpendicularly to the lock base, wherein the free end of the hook section together with the stop form a lock jaw for hanging the sheet pile lock of the Larsen sheet pile, and wherein, when viewed in a cross-sectional direction, each hooked strip has an imaginary anchor point on which the main contact point of the lock profile of the sheet pile is arranged, when it is in an ideal assembly position.

Larsen sheet piles are currently the most commonly used sheet piling worldwide. They are used for erecting sheet piling walls and so-called combination walls; i.e., arrangements made of T-beams and sheet piling. Often it is also necessary to create corners having right angles in sheet piling walls. Profiled connection sections of the kind as described in the introduction are commonly used for this purpose.

Furthermore, Larsen sheet piles are also used for erecting so-called sheet pile boxes. Sheet pile boxes are closed arrangements made of a plurality of sheet piles and/or sheeting pile sections which are connected to each other at their ends by means of profiled connection sections of the type as mentioned in the introduction, and they gird an enclosed area.

Particularly when erecting sheet pile boxes of this type, the problem arises that the sheet piles cannot be lowered into the ground precisely aligned relative to each other. Although known profiled connection sections can accommodate a certain measure of deviation, said profiled connection sections are configured in such a way that they in fact complicate the precise erection of sheet pile boxes in that even small deviations cause problems when placing the sheet piles. These deviations result in problems because, due to their special lock shape, Larsen sheet piles tend to tilt when being lowered into the ground.

The prior art teaches profiled connection sections for erecting sheet piling arrangements that couple Larsen sheet piles with their main directions of extension arranged at 90° angles in relation to each other. However, known profiled connection section are designed in such a way that they in fact complicate the precise and dimensionally correct erection of sheet pile boxes.

To ensure that the lock profiles of the Larsen sheet piles can be coupled to the profiled connection section, an imaginary anchor point is commonly defined on the holding strip of the profiled connection section, seen in the cross-sectional direction, where the sheet pile, if arranged in the ideal assembly position, is arranged by its main contact point of its lock profile.

2

It is the object of the present invention to describe a profiled connection section that is suitable for perpendicularly coupling Larsen sheet piles to each other quickly and easily, particularly while erecting sheet pile boxes.

According to the invention, the object is achieved by providing that the anchor point of each hooked strip is arranged at a specified distance which is normal to the main direction of the Larsen sheet pile that is hung on the respective other hooked strip in the ideal assembly position and that the distances between the anchor points, normal to the main direction of the Larsen sheet pile hung on the hooked strips in the ideal assembly, are identical.

The profiled connection section according to the invention provides that the two Larsen sheet piles are coupled to each other at a specified distance relative to each other by means of the profiled connection section. By choosing the anchor points on the hooked strips in such a way that the distances, which are normal to the main direction of the sheet pile that is hung on the respective other hooked strip, are identical, it is possible to erect sheet pile boxes with sheet piles that are unrestricted and that can always be lowered into the ground being properly aligned in relation to each other. Minor deviations are no longer important because, due to the existing tolerances, they can be compensated at any time. Moreover, Larsen sheet piles from different manufacturers can be easily coupled with the aid of the profiled connection section.

Further advantages are specified in the description, the dependent claims and the drawings below.

According to a particularly preferred embodiment of the profiled connection section according to the invention, the two hooked strips that extend mirror-symmetrically are connected to each other by the ends of their stops. In addition, a support strip is provided between the lock jaws facing each other, which extends centered between the two lock jaws, starting from the connection section between the two stops and facing outward. The profiled connection section that is configured in this way is used for perpendicularly connecting two Larsen sheet piles whose lock profiles are each directly outward. The profiled connection profile is then placed from the outside onto the lock profile and encompasses the two lock profiles when the profiled connection section is being driven and/or has been driven into its final assembly position. The centrally arranged support strip therein simultaneously supports the lock profiles of the Larsen sheet piles and prevents them from coming into contact with each other.

According to an alternative improvement of the profiled connection section according to the invention, the end of the stop of the one hooked strip merges with the outside of the other hooked strip at the location of the transition of the lock base thereof. The lock jaw of the one hooked strip therein is adjacently arranged relative to the outside of the lock base of the other hooked strip, while the stop of the other hooked strip juts out at a right angle from the transition of the stop of the one hooked strip with the other hooked strip and protrudes, when viewed in a cross-sectional direction, from the end of the hooked section that is arranged on the opposite side. The profiled connection section that is configured in this way is used for perpendicularly connecting two sheet piles, where the lock profile of the one sheet pile is directed outward while the lock profile of the other sheet pile is directed inward.

It may be necessary to couple three sheet piles to each other, wherein at least one of the sheet piles extends at a right angle relative to the other sheet piles. Even here, however, it is guaranteed that the distances of the anchor points,

normal to the main direction of each perpendicularly extending sheet pile, are always identical in order to achieve the desired symmetrical arrangement of the sheet piles in relation to each other.

For this purpose, a particularly preferred embodiment of the profiled connection section according to the invention provides for a further hooked strip on the profiled connection section that is identically configured relative to the other two hooked strips and serves for hanging a third Larssen sheet pile whose main direction extends at an angle of 90° relative to the other two Larssen sheet piles when it is in the ideal assembly position, and whose anchor point has a distance normal to the Larssen sheet pile extending at an angle of 90° that corresponds to the other two distances.

For the basic form of the profiled connection section, where the two hooked strips that extend mirror-symmetrically are connected to each other by the ends of their stops, it is proposed that the further hooked strip be envisioned as having its outside adjoining the outside of the hooked strip into which the Larssen sheet pile that extends at an angle of 90° is to be hung. The two hooked strips merge therein at their transitions of their lock bases with their stops in such a manner that the two hooked strips extend mirror-symmetrically with their hooked sections and their lock bases relative to each other. Using this embodiment, it is possible to couple sheet piles to each other, whereby two sheet piles arranged in a common sheet piling line while the third sheet pile extends at an angle of 90° relative to the other two sheet piles.

In an alternative basic form of the profiled connection profile, where the end of the stop of the one hooked strip merges with the outside of the other hooked strip at the transition of its lock base and stop, the further hook strip, in contrast, is formed in one piece with the transition of its lock base into the stop at the free end of the stop of the hooked strip into which the Larssen sheet pile, which extends at an angle of 90° relative to the further hooked strip, is to be hung. The further hooked strip delimits therein the lock jaw of the hooked strip with the outside of its lock base.

To ensure that the lock profile does not inadvertently become detached from the hooked strip, it is further proposed to provide for forming an elevation or thickening onto the free end of the straight stop, which is raised in the direction of the hooked section. Though only minimally, the elevation or thickening reduces the size of the lock jaw, whereby any escaping of the lock profile of the Larssen sheet pile is effectively prevented. With a wall strength of the hooked strip measuring 7 to 10 mm, the elevation or thickening is up to 2 to 3 mm thick and extends in the shape of a nose inward in the direction of the lock jaw.

The identically shaped hooked strips of the profiled connection section according to the invention preferably include a hooked section that is configured as arc-shaped, preferably substantially in the shape of a semi-circle. To facilitate hanging sheet piles by different manufacturers, experiments have shown that the inside radius of the hooked section is preferably in a range between 9 and 11 mm, whereby the lock chamber has a diameter of 18 to 22 mm and extends over an angular range of 160 to 200°, preferably 180°.

The rectilinear lock floor that immediately adjoins the hooked section is preferably 8 to 12 mm long, preferably 10 mm, and merges directly with the stop.

The inside radius of the stop that preferably corresponds to the inside radius of the arc-shaped hooked section is in a range of 9 to 11 mm.

Depending on the modulus of resistance, the hooked strip preferably has a wall strength measuring 7 to 10 mm, particularly preferred a wall strength measuring 8 to 9 mm.

To achieve an optimal arrangement of the Larssen sheet piles relative to each other, experiments have shown that the hooked strips on the profiled connection section are to be configured and arranged relative to each other in such a manner that the distance of the anchor point, normal to the main direction of the respective Larssen sheet pile, is in a range measuring 30 to 50 mm, preferably in a range measuring 35 up to 35 mm, particularly preferred 40 mm.

To compensate for measured deviations of the sheet piles, when the sheet piles originate, for example, from different manufacturers, and to ensure that the sheet piles can avoid, for example, obstacles in the ground, such as rocks, it is further proposed to configure the hooked strips in such a manner that, when viewed in a cross-sectional direction of the profiled connection section, they allow for deflective motion of the sheet piles without the risk that a given sheet pile may become inadvertently uncoupled. Accordingly, the hooked strips are preferably configured in such a way that they allow for maximally possible deflective motion of Larssen sheet piles from its main direction to $\pm 20^\circ$, preferably up to $\pm 25^\circ$. The $\pm$ symbol denotes therein that the Larssen sheet pile can be deflected clockwise or counter-clockwise by 20° and/or 25° from the ideal assembly position as defined by the main direction of the Larssen sheet pile.

On the basis of five embodiments and in reference to the drawings, the invention will be described in further detail below. Show are as follows:

FIG. 1 is a top view of a first embodiment of a profiled connection section according to the invention for connecting two Larssen sheet piles;

FIG. 2 is a top view of a second embodiment of a profiled connection section according to the invention that is based on the basic form of the first embodiment and serves for connecting three Larssen sheet piles;

FIG. 3 is a top view of a third embodiment of a profiled connection section according to the invention that is also based on the basic form of the first embodiment and serves for connecting three Larssen sheet piles;

FIG. 4 is a top view of a fourth embodiment of a profiled connection section according to the invention for connecting two Larssen sheet piles;

FIG. 5 is a top view of a fifth embodiment of a profiled connection section according to the invention that is based on the basic form of the fourth embodiment and serves for connecting three Larssen sheet piles;

FIG. 6 is a top view of a first implementation of a sheet pile box arrangement using two profiled connection sections according to the first embodiment and two profiled connection sections according to the third embodiment; and

FIG. 7 is a top view of a second implementation of a sheet pile box arrangement using two profiled connection sections according to the first embodiment and two profiled connection sections according to the third embodiment.

FIG. 1 shows a top view of a first embodiment of a profiled connection section according to the invention 10 with a constant cross-section serving for hanging the lock profiles of two Larssen sheet piles S_x and S_y at an angle of 90°, as indicated by the main directions, marked as X and Y, of the two Larssen sheet piles S_x and S_y.

The profiled connection section 10 has two identically configured hooked strips 12 and 14; the first hooked strip 12, shown below on the left in FIG. 1, where the sheet pile S_x is hung by its lock profile, will be described in further detail.

The first hooked strip **12**, with a continuous wall strength measuring 8 mm, has a semi-circularly shaped hooked section **16** that extends over an angle of 180° and has an inside diameter of 20 mm. The hooked section **16** merges into a lock base **18** that extends in a straight manner and has a length of about 10 mm. At a radius of 12 mm, the lock base **18** itself merges into a straight stop **20**. The free end **22** of the first hooked strip **12** is pointed to the stop **20** and forms together with said stop the lock jaw **24**.

The second hooked strip **14** has a mirror-symmetrical configuration relative to the first hooked strip **12** and merges via the end of its stop **26** with the end of the stop **20** of the first hooked strip **12**. A support strip **30** projects, centered in front of the two stops **20** and **26**, from between the two lock jaws **24** and **28**, which face each other, and is configured as extending symmetrically between the two hooked strips **12** and **14**.

FIG. 1 further shows that the two Larssen sheet piles **Sx** and **S_y** extend at an angle of 90° relative to each other in their main directions **X** and **Y**. Each hooked strip **12** and **14** therein, when viewed in a cross-sectional direction, has an imaginary anchor point **A** and/or **B** where the main contact point of the lock profile of the sheet pile **Sx** and/or **S_y** is arranged in an ideal assembly position.

According to the invention, the anchor point **A** and/or the anchor point **B** of the respective hooked strip **12** and/or **14** of the profiled connection section **10** is arranged in such a manner that the anchor point **A** has a specified distance **Ay**, normal to the main direction **Y** of the Larssen sheet pile **S_y** hung on the second hooked strip **14**, while the anchor point **B** has a specified distance **Bx**, normal to the main direction **X** of the Larssen sheet pile **Sx** hung on the first hooked strip **12**. According to the invention, the two distances **Ay** and **Bx** are selected as being identical to ensure that the Larssen sheet piles **Sx** and **S_y** are each located in a defined and specified position in relation to each other when they are in the hung state.

FIG. 2 shows a second embodiment of a profiled connection section **40** according to the invention that is based on the basic form of the profiled connection section **10** from the first embodiment and serves for connecting three Larssen sheet piles **Sx**, **S_y** and **Sz**.

The profiled connection section **40** has a basic form that provides, as described earlier, two hooked strips **42** and **44** that correspond to the hooked strips **12** and **14** from the first embodiment.

A third hooked strip **46** is moreover provided having a structure that corresponds to the structure of the two other hooked strips **42** and **44**. With the end of its stop **48**, the third hooked strip **46** is formed in one piece with the outside of the second hooked strip **44** into which the Larssen sheet pile **S_y** that extends at an angle of 90° is hung, particularly at the location of the transition of the lock base **50** of the second hooked strip **44** into the stop **52** thereof. Accordingly, the second hooked strip **44** delimits the lock jaw **54** of the third hooked strip **46** via the merging of the lock base **50** into the stop **52**.

As in FIG. 1, in FIG. 2 as well, the two Larssen sheet piles **Sx** and **S_y** extend in their main directions **X** and **Y** at an angle of 90° relative to each other. Here too, each hooked strip **42** and **44** therein, when viewed in a cross-sectional direction, has an imaginary anchor point **A** and/or **B** where the main contact point of the lock profile of the sheet pile **Sx** and/or **S_y** is arranged in an ideal assembly position.

Moreover, the third hooked strip **46** is also configured in such a manner that the third Larssen sheet pile **Sz**, which extends in the main direction **Z**, is also arranged by its lock

profile at an imaginary anchor point, namely anchor point **C**. The Larssen sheet pile **Sz** is therein aligned by its main direction **Z** relative to the main direction **X** of the other sheet pile **Sx**.

As FIG. 2 further shows that the anchor point **B** is arranged at a distance **Bxz** normal to the main direction **X** of the sheet pile **Sx** and simultaneously normal to the main direction **Z** of the sheet pile **Sz**, while the anchor point **A** is arranged at a distance **Ay** normal to the main direction **Y** of the sheet pile **S_y**, and the anchor point **C** at a distance **C_y** normal to the main direction **Y** of the sheet pile **S_y**. The distances **Ay**, **Bxz** and **C_y** are identical in this instance as well.

FIG. 3 shows a third embodiment of a profiled connection section **60** according to the invention that also serves for coupling three Larssen sheet piles **Sx**, **S_y**, **Sz** along three main directions **X**, **Y** and **Z**.

The profiled connection section **60** is also based on the basic form of the profiled connection section **10** from the first embodiment and, for connecting three Larssen sheet piles **Sx**, **S_y**, **Sz**, it includes three hooked strips **62**, **64** and **66**, wherein the two hooked strips **62** and **64** correspond to the hooked strips **12** and **14** from the first embodiment.

In this profiled connection section **60**, the third hooked strip **66** is provided with its outside adjoining the outside of the second hooked strip **64** where the Larssen sheet pile **S_y** is hung at an angle of 90°, wherein the two hooked strips **64** and **66** merge at the transitions of their lock base **68** and/or **70** with the stops **72** and/or **74** in such a manner that the hooked sections **76** and **78** of the two hooked strips **64** and **66** extend mirror-symmetrically relative to each other.

This embodiment also provides that the third hooked strip **66** is configured in such a manner that the third Larssen sheet pile **Sz**, which extends in the main direction **Z**, is also arranged by its lock profile at an imaginary anchor point **C**. The Larssen sheet pile **Sz** is therein aligned, by its main direction **Z**, with the main direction **X** of the other Larssen sheet pile **Sx** that is hung on the first hooked strip **62**; but, relative to the sheet pile **Sx** that is hung in the first hooked strip **62**, it is hung facing to the outside with its lock profile.

As FIG. 3 further shows that, in this embodiment as well, the anchor point **B** is arranged at a distance **Bxz** relative to the main direction **X** of the Larssen sheet pile **Sx** and simultaneously to the main direction **Z** of the Larssen sheet pile **Sz**, while the anchor point **A** is arranged at a distance **Ay** relative to the main direction **Y** of the Larssen sheet pile **S_y**, and the anchor point **C** is arranged at a distance **C_y** relative to the main direction **Y** of the Larssen sheet pile **S_y**. The distances **A_y**, **Bxz** and **C_y** are identical in this instance as well.

FIG. 4 shows a fourth embodiment of a profiled connection section **80** for connecting two sheet piles **Sx** and **S_y**.

This profiled connection section **80** also provides for two hooked strips **82** and **84** that correspond, in terms of their configuration, to the hooked strip **12**. However, with the end of its stop **86**, the second hooked strip **84** on this profiled connection section **80** merges by the outside of the first hooked strip **82** at the transition of the lock base **88** with the stop **90** of the first hooked strip **82**. The lock jaw **92** of the second hooked strip **84** therein is arranged as being adjacent to the outside of the lock base **88** of the first hooked strip **82**, and the stop **90** of the first hooked strip **82** juts out at a right angle at the transition of the stop **86** of the second hooked strip **84** to the first hooked strip **82**.

As with the first profiled connection section **10**, on this profiled connection section **80** as well, the anchor point **A** and/or the anchor point **B** of the respective hooked strip **82**

and/or **84** is/are arranged in such a manner that the anchor point A has a specified distance A_y normal to the main direction Y of the Larssen sheet pile S_y hung on the second hooked strip **84**, while the anchor point B has a specified distance B_x normal to the main direction X of the Larssen sheet pile S_x hung on the first hooked strip **82**. According to the invention, the two distances A_y and B_x are selected as being identical to ensure that the Larssen sheet piles S_x and S_y are each located in a defined and specified position in relation to each other when they are in the hung state.

FIG. 5 shows a fifth embodiment of a profiled connection section **100** for connecting three sheet piles S_x , S_y and S_z .

The profiled connection section **100** is based on the fourth embodiment and has a total of three hooked strips **102**, **104** and **106**. The two hooked strips **102** and **104** are implemented corresponding to the basic form as shown in FIG. 4.

The third hooked strip **106** merges via the end of its stop **108** with the transition of the lock base **110** in the stop **112** of the second hooked strip **104**, where the Larssen sheet pile S_y is hung, which extends at an angle of 90° relative to the first hooked strip **102** and the third hooked strip **106**.

As in the previous embodiments that have been described in reference to FIGS. 2 and 3, in this fifth embodiment, the anchor point B is arranged at a distance B_{xz} relative to the main direction Y of the Larssen sheet pile S_x and simultaneously to the main direction Z of the Larssen sheet pile S_z , while the anchor point A is arranged at a distance A_y relative to the main direction Y of the Larssen sheet pile S_y , and the anchor point C is arranged at a distance C_y relative to the main direction Y of the Larssen sheet pile S_y . The distances A_y , B_{xz} and C_y are identical in this instance as well.

The last two figures—FIGS. 6 and 7—show arrangements of sheet piles **12** that have been coupled to each other to form the so-called sheet pile boxes by using profiled connection sections according to the invention.

The arrangement **120**, as seen in FIG. 6, couples a total of four Larssen sheet piles S_A to S_D , thereby creating a cross-shaped sheet pile box **122**, wherein the sheet pile box **122** is laterally supported by two further Larssen sheet piles S_E and S_F .

To this end, the centered Larssen sheet pile S_A shown above is a so-called U-shaped sheet pile that is lowered into the ground with its lock profiles pointing outward. The adjacent Larssen sheet piles S_B and S_C are lowered into the ground rotated clockwise and/or counterclockwise by 90° and connected, with the aid of two profiled connection sections **10**, to the Larssen sheet pile S_A arranged in the center.

A further Larssen sheet pile S_D is shown in the middle, bottom that are coupled, with the aid of two profiled connection sections **40** as shown in FIG. 2, with the Larssen sheet piles S_B and S_C , which are rotated by 90° , forming the sheet pile box **122**. To further support the sheet pile box **122**, the two further Larssen pile sheets S_E and S_F are hung in the two profiled connection profiles **40**.

It is remarkable about the arrangement **120**, as shown in FIG. 6, that the totality of the Larssen sheet plies S_A through S_F are coupled to each other symmetrically and without any force.

FIG. 7 shows a further arrangement **130** where the Larssen sheet piles S_A through S_F are coupled to each other using the profiled connection sections **80** and **100**, as shown and described in FIGS. 4 and 5.

The invention claimed is:

1. A profiled connection section with a constant cross-section for coupling at least two Larssen sheet piles at an angle of 90°, comprising two identically configured hooked strips, wherein each hooked strip has a hook-shaped hook section, a lock base, which adjoins one end of the hook section and extends in a straight manner, and a stop, which adjoins the lock base, wherein the free end of the hook section together with the stop form a lock jaw for hanging the sheet pile lock of the Larssen sheet pile, and wherein, when viewed in a cross-sectional direction, each hooked strip has an imaginary anchor point defined on an inside surface of the hooked strip on which the main contact point of the lock profile of the sheet pile is arranged, when it is in an ideal assembly position,

wherein:

the anchor point of each hooked strip has a specified distance normal to the main direction of the Larssen sheet pile hung on the respectively other hooked strips in the ideal assembly position,

the distances between the anchor points normal to the main direction of the Larssen sheet piles hung in the hooked strips in the ideal assembly position are identical,

a first plane that includes an outside straight surface of the lock base and a second plane that includes an outside straight surface of the stop of each hooked strip are perpendicular, wherein the outside surfaces are spaced apart from the inside surface of the hooked strip, and the second planes that include the surfaces of the stops of adjacent hooked strips are perpendicular.

2. The profiled connection section according to claim 1, wherein the two hooked strips extend mirror-symmetrically relative to each other and are connected to each other by the ends of their stops, and wherein a support strip is provided between the lock jaws facing each other, which extends

centered between the two lock jaws and is directed outward starting from the connection area between stops.

3. The profiled connection section according to claim 1, wherein the end of the stop of the one hooked strip merges with the outside of the other hooked strip at its transition of its lock base with its stop, wherein the lock jaw of the one hooked strip is arranged adjacent relative to the outside of the lock base of the other hooked strip, and wherein the stop of the other hooked strip juts out at a right angle from the transition of the stop of the one hooked strip to the other hooked strip and protrudes, viewed in cross-sectional direction, beyond to the end of the hooked section arranged opposite.

4. The profiled connection section according to claim 1, wherein a further hooked strip identically configured as the other two hooked strips is provided, which serves for hanging a third Larssen sheet pile whose main direction extends at an angle of 90° relative to one of the two other Larssen sheet piles in the ideal assembly position, and whose anchor point has a distance normal to the Larssen sheet pile extending at an angle of 90°, which corresponds to the two other distances.

5. The profiled connection section according to claim 4, wherein the further hooked strip is provided with the end of its stop on the outside of the hooked strip, where the Larssen sheet pile that extends at an angle of 90° is to be hung, at the transition of its lock base and its stop in such a manner that the transition delimits the lock jaw of the further hooked strip.

6. The profiled connection section according to claim 4, wherein the further hooked strip is provided with its outside on the outside of the hooked strip, where the Larssen sheet pile that extends at an angle of 90° is to be hung, wherein the two hooked strips merge at their transitions of their lock bases with their stops in such a manner that the two hooked strips extend mirror-symmetrically by their hooked sections and their lock bases.

7. A profiled connection section according to claim 4, wherein the further hooked strip is formed in one piece with its transition of its lock base with its stop on the free end of the stop of the hooked strip where the Larssen sheet pile extending at an angle of 90° opposite the further hooked strip is to be hung, wherein the further hooked strip delimits by the outside of its lock base the lock jaw of the other hooked strip.

8. The profiled connection section according to claim 1, wherein a thickening is formed on the free end of the straight stop that is raised in the direction of the hooked section.

9. The profiled connection section according to claim 1, wherein each hooked strip is formed as arc-shaped, preferably substantially in the shape of a semi-circle, and wherein the hooked strip has an internal radius in a range from 9 to 11 mm that extends over an angle range from 160 to 200°, preferably corresponding to 180°.

10. The profiled connection section according to claim 9, wherein the transition of the lock base with the stop has an internal radius that is in a range between 9 and 11 mm and that preferably corresponds to the internal radius of the arc-shaped hooked strip.

11. The profiled connection section according to claim 1, wherein each the hooked strips have a wall strength that measures 7 to 10 mm, preferably 8 to 9 mm.

12. The profiled connection section according to claim 1, wherein each distance of the anchor point is normal to the main direction of the Larssen sheet pile and in a range between 30 and 50 mm, preferably in a range between 35 and 35 mm, and preferably corresponding to 40 mm.

13. The profiled connection section according to claim 1, wherein the maximally possible deflection of the Larssen sheet pile from its main direction is up to $\pm 20^\circ$, preferably up to $\pm 25^\circ$.
